UNITED STATES PATENT OFFICE.

EDWARD H. MCCLINTOCK, OF WEST SOMERVILLE, MASSACHUSETTS, ASSIGNOR OF ONE-HALF TO EDWARD B. MARTIN, JOHN D. CROSBY, AND CHESTER S. DAY AND ONE-FOURTH TO ARTHUR S. MARTIN, ALL OF BOSTON, MASSACHUSETTS.

CEMENTITIOUS BUILDING-BLOCK.

No. 897,552.

Specification of Letters Patent.

Patented Sept. 1, 1908.

Application filed June 11, 1906. — Serial No. 321,274.

To all whom it may concern:

Be it known that I, EDWARD H. MCCLINTOCK, a citizen of the United States, residing at West Somerville, in the county of Middlesex and State of Massachusetts, have invented certain new and useful Improvements in Cementitious Building-Blocks, of which the following is a specification.

My invention relates, in general, to building blocks of cementitious compositions, and has for its object to provide a block embodying provisions whereby a circulation of air throughout a wall built therefrom is made possible, said blocks furthermore being so constructed that the passage of moisture from the weather side of the block to the interior surface by capillary or like action is reduced to a minimum, resulting in a dry wall. I attain these objects by the block illustrated in the accompanying drawings, in which

Figures 1 and 2 respectively show the male and female components of said block. Fig. 3 is a view of the entire block composed by combining the said male and female components.

Referring to Fig. 1 the male component consists of a block preferably rectangular in general outline, having a recess, preferably arch-shaped, cored in the bottom part thereof, and of such size as to remove the maximum amount of material from the block consistent with preserving the desired strength in the same. To that end the arch springs from near the edges of the block at 1, the height of the same being such as to reach, at its crown comparatively near the upper surface of the block. The width of the recess is such as to leave but a thin shell of material near the rear face of the block as it appears in Fig. 1.

Laterally projecting from the crown of the arch is the tongue 2 preferably having its upper surface flush with the top of the block, and its lower surface in general conforming to the shape of the crown of the arch from which it projects. The female component shown in Fig. 2 is a block generally similar in external shape, size, etc., to the male component, and embodies a recess similar to that described in connection with the male component. The crown of the said arch is, however, cut away to form an opening 3 in the top of the said block of a shape and size corresponding to that of the tongue 2.

In practice my block is formed in its entirety by combining the male and the female components to form the composite block as shown in Fig. 3, the said components preferably being held together through the dovetailing of the tongue 2 of the male component within the opening 3 of the female component, as is shown in the said Fig. 3.

When the components are to be set together, which is done preferably at the time when the block is being positioned in the wall under process of construction, mortar is spread in usual manner on the surfaces where the block will bear against the blocks adjacent thereto, and the female component, preferably is then set with reference to the exposed surface of the wall. Mortar is next spread either on the surfaces 4, 4, which form the sides of the tongue 2, or on the surfaces 5, 5, forming the sides of the opening 3, as well as on the surfaces where the male component will bear against adjacent blocks. The male component may now be set, being so placed that the tongue 2 enters into and fills the opening 3, being forced thereinto until the upper surfaces of the two components are substantially in the same plane, the said tongue 2 serving as a keystone, as it were, filling the opening 3 in the female component, and completing the arch over the recess of said component. The adjacent faces 6 and 7, of the two components are not placed in contact, but are somewhat separated from each other, as by the spacing blocks 8, 8, or in any other desired manner, so as to leave the slits 9, 10, and 11, which form passages leading from the arch shaped recess of the block to its upper surface. The separation of the block components may also be effected without use of the blocks 8, 8, by making tongue 2 of a greater length than the recess 3. In such case the block components may be set together so that the tongue preferably fills recess 3 completely, thus doing away with slit 10. The length of tongue 2 should exceed that of recess 3 enough to cause the separation of the block components along the adjacent faces 6 and 7, forming slits or passages 11 and 12 operating as before described to afford air communication between top of block and recess.

In laying up a wall with my blocks it is customary to place the blocks so that they break joints with each other, a block of one

course being placed so that its ends rest on the crowns of the arches of two adjacent blocks of the next lower course. The arched recess of the upper block is thus substantially centrally located above the meeting ends of the blocks of the said lower course, and the slits 9 and 11, and also slit 10 in part, afford a communication between the recesses of the blocks in one course with those of the course 10 lying next above or below the same.

By reason of the intercommunication afforded by the passages or slits 9, 10, and 11, a free circulation of air throughout the wall is made possible whereby the same is kept in 15 a well-ventilated and dry condition. Furthermore owing to the fact that the component of the block which is exposed to the weather is separated from its companion component by a mortar joint along their contacting surfaces 4, 4 and 5, 5, and is also separated by mortar joints from the blocks adjacent thereto, the penetration of moisture, due to capillary or other action, from the exposed or weather surface, is largely arrested 20 by the said mortar joints so that the blocks forming the interior of the wall are maintained practically free from moisture.

It is evident that the advantages of my invention may be substantially realized in a 30 block having a recess which is not technically included in the term "arch-shaped"; provided that said recess be so formed as to cause the inclosing sides, preferably at the ends of the block, to gradually thicken towards the top of the block so as to provide an upper surface of sufficient thickness and strength to support the superincumbent blocks resting thereon.

Having described my invention, what I 40 claim and desire to secure by Letters Patent is:—

1. A cementitious building block comprising two interengaging components, forming, in their engaged position a block whose 45 under portion has a cored away recess opening from, and largest near, the bottom surface of the block, and extending with a gradually decreasing horizontal area into the upper portion of the same, said components 50 engaging by a tongue extending from the upper surface of one component, and adapted to fit within a corresponding recess in the surface of the other component.

2. A cementitious building block comprising two interengaging components, forming, in their engaged position a block whose 55 under portion has a cored away recess open-

ing from, and largest near, the bottom surface of the block, and extending with a gradually decreasing horizontal area into the 60 upper portion of the same, said components engaging by a tongue extending from the upper surface of one component, and adapted to fit within a corresponding recess in the upper surface of the other component, and 65 being provided with means whereby the said components are separated along their adjacent faces so as to establish passages leading from the recess to the surface of the block.

3. A cementitious building block comprising two interengaging components, forming, in their engaged position a block whose under portion is partially cored away to 70 form a recess opening from, and largest near, the bottom of, said block, the sides of said recess, converging towards the upper portion of said block, the height of said recess being less than that of the block so as to leave the upper surface thereof substantially entire; said components engaging by 75 a tongue laterally extending from the upper surface of one component, and adapted to fit within a corresponding recess in the surface of the other component.

4. A cementitious building block comprising two interengaging components, forming, in their engaged position, a block whose under portion has a cored-away arch shaped recess contained in part in each component, said components engaging by a tongue integral with crown of one component and 80 adapted to fit within a corresponding recess in the crown of the other component.

5. A cementitious building block comprising two interengaging components forming, in their engaged position a block whose under portion is partially cored away to 95 form an arch shaped recess contained in part in each component, said components engaging by a tongue integral with, and projecting 100 from the crown of one component and adapted to fit within a corresponding recess in the crown of the other component, and having spacing devices whereby said components are separated along their adjacent 105 faces so as to establish passages leading from the recess to the surface of the block.

In testimony whereof I affix my signature in presence of two witnesses.

EDWARD H. MCCLINTOCK.
